United States Patent Office.

EDWARD KING, OF TAUNTON, MASSACHUSETTS.

Letters Patent No. 70,860, dated November 12, 1867.

IMPROVED DOOR-LATCH.

The Schedule referred to in these Letters Patent and making part of the same.

TO ALL WHOM IT MAY CONCERN:

Be it known that I, EDWARD KING, of Taunton, in the county of Bristol, and State of Massachusetts, have invented a new and improved Latch for Doors, etc.; and I do hereby declare that the following is a full, clear, and exact description thereof, which will enable those skilled in the art to make and use the same, reference being had to the accompanying drawings, forming part of this specification.

The present invention relates to a latch for doors, etc., which consists in a novel connection between the latch and handle or knob-spindle. In the accompanying plate of drawings my improved latch for doors is illustrated—

Figure 1 being an inside view of the casing in which the latch is arranged to move, showing the connection between it and the knob-spindle,

Figure 2 a section taken in the plane of the line $z z$, fig. 1, and

Figure 3 a cross-section in the plane of the line $y y$, fig. 2.

Similar letters of reference indicate corresponding parts.

A, in the drawings, represent the latch-bolt, arranged within a tube or case, B, to move out and in through a plate, C, to which the said case B is fastened. The tail or inner end D to the latch-bolt A terminates in a spindle, E, which spindle forms a continuation of the bolt A, and at its outer end moves through one side to a hub, F, of the knob-spindle G. The hub F and spindle G are both so constructed as to interlock with each other, and thus, as the spindle G is turned in a direction, either to the right or left, as the case may be, to cause the said hub to slide within the case B, either more or less, according to the form of construction, and in a corresponding or opposite direction to that in which the knob-spindle is turned. To the hub F is an extension-arm, H, that, at its outer end, is arranged to abut against a lever or pawl, I, connected and interlocked with the latch-bolt A, as shown in fig. 1 more particularly. J is a spiral or coiled spring, around extension E to latch-bolt.

By the above-described arrangement of parts between the latch-bolt and knob-spindle, as the knob is turned in the proper direction, the bolt will be drawn in, when, releasing the knob, the spring J acts to throw out the bolt again, as is obvious without any further description.

I claim as new, and desire to secure by Letters Patent—

The combination of the hub F to knob-spindle, having extension-arm H, in combination with a latch-bolt carrying pawl I, when all arranged together for operation substantially as and for the purpose described.

EDWARD KING.
